UNITED STATES PATENT OFFICE.

DANA B. BURNS, OF ASHEVILLE, NORTH CAROLINA.

VALVE MECHANISM FOR INTERNAL-COMBUSTION ENGINES.

Application filed April 8, 1926. Serial No. 100,625.

This invention relates to valve mechanisms for internal combustion engines and more particularly to the construction and arrangement of the exhaust and intake manifolds in a manner permitting the use therewith of sleeve valves, housing these manifolds and controlling communication between the manifolds and the cylinders of the engine.

An important object of the invention is to provide a consolidated intake and exhaust manifold structure so formed that a water jacket combined with these manifolds in cylindrical form permits complete insulation of the exhaust manifold by the intake manifold and this water jacket so as to prevent undue heating and consequently undue warping of the sleeve valves while providing for heating of the incoming charge.

A further object of the invention is to provide a novel and improved mounting for the combined intake and exhaust manifold permitting the same to be housed in the head structure of the engine.

A still further object of the invention is to provide a structure such that the sleeve valves need have but a very limited movement in opening and closing the ports of the engine, thus reducing to a minimum the wear on such valve.

A further object of the invention is to produce a device of this character permitting the use of compression rings between the inner sleeve valve and the combination manifold.

A further object of the invention is to improve the structure shown in my prior application, No. 74,578, on valve mechanisms for internal combustion engines, filed December 10, 1925, of which application this application is in part a continuation.

A more specific object of the invention is to provide a manifold construction of the character above described which is shiftable within the sleeve valves transversely of the sleeve valves and toward the ports with which the sleeve valves coat so that a tight joint is maintained at all times between the manifold and sleeve valves, between the sleeve valve structures themselves and between the sleeve valves and the walls of the bore in which the valves and manifold are arranged.

These and other objects I attain by the construction shown in the accompanying drawings, wherein for the purpose of illus-

tration is shown a preferred embodiment of my invention and wherein:—

Figure 1 is a vertical sectional view showing operating mechanism for the valves;

Figure 2 is a longitudinal sectional view 60 through the manifold and valves;

Figures 3, 4 and 5 are transverse sectional views through the manifold taken at the carburetor intake and exhaust and intake ports respectively; 65

Figure 6 is a vertical sectional view through the manifold;

Figures 7 and 8 are side elevations of the valves employed;

Figure 9 is a section on the line 9—9 of 70 Figure 2.

Fig. 10 is a perspective of the crank shaft 40, showing the relative positions of the cranks 43^a thereon.

Referring now more particularly to the 75 drawings, the numeral 10 generally designates a block of an internal combustion engine having cylinders 11 each provided with spaced intake and exhaust ports 12 and 13. Between the outer wall 14 of the block 80 and the cylinders, a water space 15 is provided in the usual manner. Extending longitudinally of the head at one side thereof is a bore 16 into which the ports 12 and 13 open. The bore 16 has one end thereof 85 opening into a chamber 17 and the opposite end thereof has a reduced opening 18 through a water jacketed wall 19, the water jacket of which communicates with the water space 15 of the engine. This wall 19 90 has likewise formed therethrough a port 21, both the opening 18 and port 21 being sealed from the water space 20 of the wall 19. These openings, as more clearly shown in Figure 9, are elongated transversely of the 95 bore 16 upon or parallel to an axis intersecting the ports 46.

The numeral 22 generally designates a combination manifold having an external cylindrical wall 23 of less diameter than 100 the internal diameter of the bore 16. The ends of the combination manifold are closed, as indicated at 24 and 25 respectively, the end 25 having a reduced extension 26 engaging the upper and lower walls of the 105 bore 18 of the head and being of less length than the thickness of the wall 19. The outer end of the bore 18 is surrounded by an exhaust fitting 27 and through the wall of the bore 16 an adjusting and retaining element 110

28 is extended for engagement in a socket 28^a formed in the wall of the manifold 22 so that the manifold is kept in proper relation to the wall 19. Interiorly, the combination 5 manifold is formed to provide two longitudinal chamber Ex and In forming the exhaust and intake manifolds for the engine. The exhaust manifold is spaced throughout its length from the outer wall 23 of the 10 combination manifold and is offset to one side of the combination manifold so that a greater space is provided at one side of the exhaust manifold than at the other. The major portion of the larger space thus 15 formed is occupied by the intake manifold In. Each of the exhaust and intake manifolds is substantially in the form of a quarter segment of a circle, as is more clearly shown in Figure 3 and these quarter segments are 20 offset to the opposite side of the manifold from that opposed to the intake and exhaust ports of the engine.

The combination manifold has in its outer wall 23 in opposition to the intake and exhaust openings 12 and 13 of the cylinders intake and exhaust openings 12^a, 13^a, each of which is in communication with its respective manifold through a narrow walled passage 29. This passage extends through a 25 space 30 which is formed by the offsetting of the exhaust and intake ports transversely of the combination manifold from the intake and exhaust openings 12^a, 13^a and this space 30 forms a water space which, by 30 reason of the spacing of the exhaust manifold from the wall of the cylinder at 13, as above described, continues about the exhaust manifold on all sides thereof not occupied by the intake manifold. In this way, 35 a complete insulation of the exhaust manifold is had and a substantially uniform temperature of the outer wall 23 of the combination manifold in short. The water space 30 is connected at one end with a duct 32 communicating with the forward end of the cylinder and at its opposite end with a duct 33 extending through the port 21 and communicating with the rear end of the cylinder water jacket. When originally installed, both the reduced extension 26 and the duct 33 are arranged at the outer ends of their openings 18 and 21 with respect to the cylinder so that the manifold may be 40 adjusted toward the cylinder. The ducts 32 and 33 are rendered flexible in any suitable manner, as generally designated at 34, to 45 permit this adjustment.

By this construction, a circular combination manifold results having arranged interiorly thereof a substantially semi-circular structure comprising the exhaust and intake manifolds. The intake manifold structure 50 serves to support and insulate a portion of the exhaust manifold. This insulation taken 55 with the water insulation provided is such

that it permits the outer wall 23 of the combination manifold to be made relatively heavy so that this outer wall may be provided intermediate each pair of ports 12^a, 13^a thereof and upon its exterior with a 60 groove receiving an expansion packing ring 34. These expansion packing rings will engage against the interior of a sleeve valve 35 which preferably slides upon the interior of a second sleeve valve 36, the exterior 65 diameter of which is such that it has a sliding fit in the bore 16. These sleeve valves furthermore may be operated in any suitable manner and may be ported in any manner which is found desirable. I, however, prefer to provide within the compartment 17 a stub shaft 37 driven from the shaft 38 of the engine. Mounted in a bearing 39 is a shaft 40 bearing a gear 41 meshing with a pinion 42 carried by the stub 85 shaft 37. The outer end of the shaft 40 is formed as a double crank 43, the cranks 43^a of which are spaced apart ninety degrees. Each valve 35 and 36 has a head 44 including a cross head yoke 45 in which its associated crank of the double crank 43 operates. Each sleeve valve is then provided with a port 46 for each port of the engine, these ports being computed with the crank arrangement above designated. I have 90 found that by use of this crank arrangement and of a port for each cylinder of the engine in each of the valves, it is only necessary that a very slight movement of each of the valves take place in order that proper valve openings may be provided for the cylinders. Each of the valves has formed therethrough a slot 47 for the passage of a carburetor connection communicating with the intake In. It is, of course, understood that the exhaust 95 manifold has an outlet port through the extension 26 hereinbefore described.

It will be obvious from the foregoing that an engine provided with a valve mechanism constructed in accordance with my invention and a combination manifold such as described will embody all of the advantages obtained by the use of the ordinary sleeve valve construction of automobile engines and at the same time, these valves are rendered accessible and readily removable without a complete tearing down of the engine. It will furthermore be noted that this is accomplished with the use of but two 110 sleeve valves, as differentiated from two 115 sleeve valves, for each cylinder in the construction above referred to.

By insulating the exhaust manifold and the wall of the combination manifold adjacent the ports of the engine, the water insulation is permitted to act upon the port walls and considerably reduce the temperature of the exhaust gases before they reach the manifold proper so that but a slight insulation of the exhaust manifold from the 120 125 130

portion of the combination manifold lying remote from the intake and exhaust ports will prove sufficient.

In order to maintain at all times a tight engagement between the sleeve valves themselves and between the sleeve valves and the wall of the bore 16 at the ports 12 and 13 and further between the sleeve valves and the manifold, I provide means for constantly urging the manifold 22 toward the ports. This I accomplish by forming in the walls of the bore 16 opposite the ports 12 and 13 bores 48, the outer wall having an outstanding flange 49 providing a continuation of the bore which is externally screw-threaded. Slidable within these bores are plungers 50 extending through slots 51 formed in the sleeve valves and engaging and fitting at their inner ends against the manifold. These plungers are preferably hollow and house a spring 52, the outer end of which engages against a cap 53 which may be adjusted to regulate the tension of the spring. These springs constantly urge the manifold toward the ports with the result that any slack caused by wear will be removed and a tight joint maintained at all times. The elongation of the openings 18 and 21 is made sufficient to compensate for wear during the life of the engine.

It will be obvious that many changes are possible in the construction above set forth without in any manner departing from the spirit of my invention and I accordingly do not limit myself to such specific structure except as hereinafter claimed.

I claim:

1. In an internal combustion engine, a water jacketed head having a longitudinally extending bore and intake and exhaust ports for the cylinders of the engine, a combination manifold structure having an external wall of less diameter than the diameter of the bore supported from one end wall of the bore and extending thereinto, an intake manifold within the outer wall and having a portion of the wall thereof formed by said outer wall, an exhaust manifold likewise within the outer wall and supported from the intake manifold, the walls of said exhaust manifold being spaced from said outer wall, said space being in communication with the water jacket of the head, ports in said outer wall communicating with said intake and exhaust manifolds and opposing the ports of the engine, a sleeve valve surrounding the combination manifold and axially shiftable to align ports formed therein with the intake and exhaust ports of the head and manifold and means for shifting said sleeve valve.

2. In an internal combustion engine, a water jacketed head having a longitudinally extending bore and intake and exhaust ports for the cylinders of the engine, a com-

bination manifold structure having an external wall of less diameter than the diameter of the bore supported from one end wall of the bore and extending thereinto, an intake manifold within the outer wall and having a portion of the wall thereof formed by said outer wall, an exhaust manifold likewise within the outer wall and supported from the intake manifold, the walls of said exhaust manifold being spaced from said outer wall, said space being in communication with the water jacket of the head, ports in said outer wall communicating with said intake and exhaust manifolds and opposing the ports of the engine, a sleeve valve surrounding the combination manifold and axially shiftable to align ports formed therein with the intake and exhaust ports of the head and manifold, means for shifting said sleeve valve and means resiliently urging the manifold transversely of the bore and toward the intake and exhaust ports of the engine.

3. In an internal combustion engine, a water jacketed head having a longitudinally extending bore and intake and exhaust ports for the cylinders of the engine, a combination manifold structure having an external wall of less diameter than the diameter of the bore supported from one end wall of the bore and extending thereinto, an intake manifold within the outer wall and having a portion of the wall thereof formed by said outer wall, an exhaust manifold likewise within the outer wall and supported from the intake manifold, the walls of said exhaust manifold being spaced from said outer wall, said space being in communication with the water jacket of the head, ports in said outer wall communicating with said intake and exhaust manifolds and opposing the ports of the engine, a sleeve valve surrounding the combination manifold and axially shiftable to align ports formed therein with the intake and exhaust ports of the head and manifold, means for shifting said sleeve valve and spring pressed plungers directed through the wall of the bore and said valve to engage the manifold and yieldably urge the same toward the ports of the engine.

4. A combination manifold comprising an outer wall having ports formed therein along one side thereof, an intake manifold within the wall thereof and having a portion of the wall thereof formed by said outer wall, an exhaust manifold likewise within the outer wall and having a portion of its wall formed by the wall of the intake manifold, the remaining portions of the walls of the intake and exhaust manifolds being spaced from said outer wall to provide a water space, said intake and exhaust manifolds being of less width than the outer wall and being arranged at the opposite side of

the casing formed by the outer wall from the ported wall thereof to thereby provide between said ports and the intake and exhaust manifolds a relatively wide water space, the connections between said ports and said intake and exhaust manifolds extending through said space and being in the form of narrow walled passages.

5. In an internal combustion engine, a
10 water jacketed head having a longitudinally
extending bore and intake and exhaust ports
for the cylinders of the engine opening to
said bore; a combination manifold structure
having an external wall of less diameter than
15 the diameter of the bore arranged within
the bore, said external wall having openings
aligning with the intake and exhaust ports
of the head, intake and exhaust manifolds
within said external wall and arranged at

the opposite side thereof from said openings
to thereby provide a relatively wide space
between the openings and said intake and
exhaust manifolds, walled passages connecting
said openings with their respective mani-
folds, a sleeve valve surrounding the combi-
nation manifold and axially shiftable to
align ports formed therein with the intake
and exhaust ports of the head and mani-
fold, means for shifting said sleeve valve,
means resiliently urging the combination
manifold transversely of the bore and to-
ward the intake and exhaust ports of the
engine and means connecting said space with
the water jacket of the head.
